UNITED STATES PATENT OFFICE.

EDGAR KIDWELL, OF MILWAUKEE, WISCONSIN, ASSIGNOR TO KIDWELL BOILER COMPANY, OF MILWAUKEE, WISCONSIN, A CORPORATION OF WISCONSIN.

STEAM BOILER.

Application filed December 4, 1923. Serial No. 678,409.

To all whom it may concern:

Be it known that I, EDGAR KIDWELL, a citizen of the United States, and resident of Milwaukee, in the county of Milwaukee and 5 State of Wisconsin, have invented certain new and useful Improvements in Steam Boilers, of which the following is a specification.

This invention relates to water-tube boilers wherein are employed two or more upper steam-and-water drums connected by overcomer or superheater tubes in such a manner that the steam which is liberated from the water contained in the water space of 15 one or more drums is delivered to the steam space of another drum.

An object of my invention is to construct a boiler having provisions whereby the impurities contained in the moisture that is 20 carried over by the liberated steam are effectually eliminated before the steam passes from the boiler for service.

Another object of my invention is to provide a novel form of superheater for the 25 purified steam preparatory to its discharge from the boiler.

According to my invention the drum into which the liberated steam is delivered is equipped with a shelf or baffle so located 30 therein as to intercept and separate the incoming steam and the dried impurities carried over thereby, which impurities are thence deflected to the water contained in the drum and precipitated therein in such 35 a manner that the deposit can be readily withdrawn by means of a blow-off connection in the bottom of the drum. The purified steam is caused to pass from the drum to and through a series of secondary super- 40 heating tubes leading to a suitable header from which the steam is finally delivered for service. Such superheating tubes are positioned directly beneath and longitudinally of the primary superheating tubes so as to 45 be subjected to the efficient action of the furnace gases in their upward, rearward and downward flow through the boiler structure; all as hereinafter fully described and claimed.

50 Referring to the drawing, which represents a longitudinal vertical section of the upper portion of one type of water-tube boiler containing two steam-and-water drums and embodying my invention. 2, 3

designate two upper steam-and-water drums, 55 whereof the former constitutes a rear steam-disengaging element which is included in the main path of water circulation, and whereof the latter drum 3 constitutes a front steam-receiving element remote from such 60 circulation path. The steam spaces of the respective drums are connected by superheater tubes or "overcomers" 4, and the water spaces of the respective drums are connected by means of opposite-flow tubes 65 5 which function to establish a supplementary water circulation between the two drums and maintain therein a uniform water level, as more fully described in Letters Patent of the United States No. 1,442,- 70 433 dated January 16, 1923, to which reference may be had.

The steam which is liberated from the circulating boiler water in the drum 2 flows through the overcomer tubes 4 into the steam 75 space of the drum 3, such steam in its passage through the tubes 4 being subjected to a gas temperature outside of the tube sufficiently high to superheat the steam. The steam upon entering the overcomer tubes 80 carries with it a certain percentage of moisture which is in consequence of the superheat evaporated in its passage through the tubes, and in consequence any impurities that are held in solution or in suspension in the entrained moisture are left as a residue from the evaporation and fall, as an impalpable dust, to the bottom of the tubes, which dust is, perforce, swept onward by the steam 85 into the forward drum. In the absence of 90 separating means and when the steam in saturated or wet condition is drawn directly from the boiler nozzle, all impurities contained in it are drawn into the steam outlet pipe from the drum 3, resulting in much 95 trouble, such, for example, as the erosion of the prime movers, the scoring of the engine cylinders and valves, and the clogging of steam-flow leads and traps.

Engineers have only recently realized 100 what a great percentage—as high as 90%—of the total impurities in the water is swept out into the steam pipe by wet steam. The serious consequences of allowing such a volume of impurities to go out with the steam 105 can be realized from the fact that it has been found in some plants that the amount of sediment blown out through the pipe 7, in

my invention as below described, is double the amount blown out through the bottom blow-off valves of the boiler.

In pursuance of my invention I arrange 5 within the drum 3, above the surface of the water contained therein, a baffle 6 upon which the incoming steam and dust impinge at an acute angle, which steam is thus deflected forward and prevented from striking 10 the water contained in the drum, while the dust is swept off the baffle and precipitated into the water. This dust, becoming saturated, settles to the bottom of the water in the drum and forms a sediment or sludge 15 that can be readily removed by and through the blow-off pipe 7 extending from the bottom of the drum.

In order to subject the purified steam to a high degree of superheat before the discharge of the steam from the boiler, I connect the steam space of the drum 3 by means 20 of a series of steam flow leads 8 with a header 9 which is illustrated as arranged above and longitudinally of the said drum. 25 These leads are entered into the drum in a plane above the baffle 6, and they are located within the space directly beneath and longitudinally of the overcomers 4 in such manner that the furnace gases in their upward, rearward and downward passage from 30 the furnace chamber to the stack, flow amongst and effectively heat the leads 8, such leads thus constituting a steam superheater. Since the impurities are eliminated 35 from the steam before it has an opportunity to enter the superheater, the walls of the later do not become encrusted with secretions and thus overheated, and therefore the life of the superheater is greatly prolonged, 40 and its efficiency as to absorbing heat from the gas and transmitting it to the steam is constantly maintained.

It is to be noted that the superheater leads comprise a series of U-form tubes arranged 45 in nested relation with their respective ends directly connected with the drum 3 and header 9 so as to insure a rearward and forward flow of the steam, and since these tubes are located in the space above the main 50 cross-baffle 10 and the main banks of boiler

tubes 11, the superheater tubes 8 are not only subjected to the efficient heat of the furnace gases, but they can be readily inspected, cleaned, removed or replaced, as occasion may require.

It is to be understood that I do not limit myself to the structural details herein disclosed, as the construction may be modified within the principle of my invention and the scope of the appended claims.

I claim—

1. In a water-tube boiler having upper steam-and-water drums whereof one constitutes a steam-disengaging element included in the main path of water circulation, and another drum constitutes a steam-receiving element remote from said path, and having also opposite-flow tubes connecting the water spaces of the drums, and overcomer tubes between the steam spaces of the respective drums, a baffle member arranged within the steam-receiving element at an angle to the delivery path of the overcomer tubes, a steam-receiving header, steam-flow leads connecting the steam-receiving element to the header, said leads extending directly below and longitudinally of the over-comer tubes to constitute a superheater, and a blow-off pipe for the bottom of the steam-receiving element.

2. In a water-tube boiler having upper steam-and-water drums whereof one constitutes a steam-disengaging element included in the main path of water circulation, and the other drum constitutes a steam-receiving element remote from said path, and having also opposite flow tubes connecting the water spaces of the drums, and overcomer tubes between the steam spaces of the respective drums, a steam-receptacle, and a series of U-shaped superheater tubes located within the space below and longitudinally of the overcomer tubes and connected at their respective ends with the steam-receiving element and the said receptacle.

Signed at Milwaukee, in the county of Milwaukee and State of Wisconsin, this 30th day of November, A. D. 1923.

EDGAR KIDWELL.
